D. R. McGINNIS.
AWNNG VENTILATOR.
APPLICATION FILED MAY 23, 1914.

1,103,980.

Patented July 21, 1914.

UNITED STATES PATENT OFFICE.

DAVID R. McGINNIS, OF FRESNO, CALIFORNIA.

AWNNG-VENTILATOR.

1,103,980.

Specification of Letters Patent.

Patented July 21, 1914.

Application filed May 23, 1914. Serial No. 840,511.

To all whom it may concern:

Be it known that I, DAVID R. McGINNIS, citizen of the United States, residing at Fresno, in the county of Fresno and State of California, have invented certain new and useful Improvements in Awning - Ventilators, of which the following is a specification, reference being had therein to the accompanying drawing.

10 This invention relates to an awning ventilator and has for its principal object the production of a device which is so formed as to conduct the heated air from the interior to an opening and allow the same to be expelled therefrom.

15 Another object of this invention is the production of an awning ventilator comprising an opening for allowing the heated air to pass therethrough and with a flap carried adjacent this opening for preventing the heated air from passing beyond the above-mentioned opening.

20 With these and other objects in view this invention consists of certain novel combinations, constructions, and arrangements of parts as will be hereinafter fully described and claimed.

25 In the accompanying drawing:—Figure 1 is a detailed perspective view of the awning ventilator showing the same in use. Fig. 2 is a central vertical section taken through the awning ventilator. Fig. 3 is an enlarged fragmentary sectional view of the ventilating portion of the awning. Fig. 4 is a 30 fragmentary plan view of the ventilating portions of the device being shown in sections to illustrate the reinforcing means. Fig. 5 is a fragmentary sectional view taken on the line 5—5 of Fig. 2. Fig. 6 is a vertical section taken through a slightly modified 35 form of the ventilator.

40 Referring to the accompanying drawing by numerals 1 designates the top of the awning having the depending sides 2. This awning is of course formed of the usual construction, having the ropes 3 for raising and lowering the same. The object of this invention is to provide this awning with a simple and efficient means for conducting 45 the air to an opening formed in the top 1 and allowing the air to pass from the interior of the awning.

45 It will be seen that the top of the awning is provided with a rectangular opening 4 which extends transversely there-across adjacent its upper portion. This opening 4 is

5 formed, by cutting the top 1 transversely and then bending the strips 5 back under the top 1 and sewing or otherwise fixedly securing the strips to the top. In this manner it will be seen that the side edges of the top 1 adjacent the opening 4 will be greatly reinforced. After the opening has been formed in this manner, cords or lines 6 may be passed through the strips 5 as shown in Fig. 60

65 4. In forming the device as disclosed in Fig. 4, one cord or line is used so as to extend twice across the breadth of the opening 4. The line may be passed through the lower strip 5 and then allow both ends of 70 the same to pass in parallel spaced relation across the opening 4. The free end of this line may then be passed into the strip 5 and sewn or otherwise secured within this strip.

75 It will be seen that since one cord or line 6 merely extends twice across the opening, any danger of the awning sagging or the opening losing its correct shape may be eliminated since the cords will not be of sufficient length to give when in use. In 80 order to guide the heated air within the awning through this opening 4 there is provided a flap 7. This flap 7 has its edge portion forming a secondary strip 8 which is secured fixedly to the top 1 by sewing the 85 same or riveting the same thereto. This flap 7 depends in a vertical position owing to its own weight and is provided with slots 9 formed adjacent its end portions for accommodating the ropes 3 used for raising and 90 lowering the awning. This flap 7 is not secured to the sides 2 of the awning but it is only secured at its upper edge and will thereby be allowed to easily move when it is necessary for the same to do so. Providing 95 the same with the slots, it will be seen that the ropes 3 will not interfere with the flap 7 always hanging in its correct position when the awning is lowered as disclosed in Fig. 1. Since this flap 7 is secured to the top 1 of the awning above the opening 4 it will be seen that when the sun shining upon the awning radiates heat within the same, the heated air will pass upwardly and upon striking the flap 7 will be guided through 100 the opening 4 and expelled into the outer atmosphere. This will prevent the heated air from passing into the room and will allow the heated stagnant air within the awning to be easily expelled therefrom.

105 110 By referring to Fig. 6 it will be seen that the opening 4 and reinforcements are all

constructed similar to the preferred form. In this device, however, the upper portion of the awning is bent backwardly upon itself as disclosed at 10 so as to provide an integral depending flap 11 for performing the functions of the flap 7 of the preferred form. In this device, however, it will be seen that the flap is formed integral and will therefore eliminate a considerable part of the 5 tendency to be torn from engagement with the awning. It will further be noted that the flap, if so desired, may be provided with a button-hole 12 in engagement with the button 13 whereby the flap may be swung 10 back to engage the button if it is so desired. Since the flap hangs in a vertical position it will conduct the heated air to the opening 4 and will at the same time prevent the rays of the sun passing through the opening 15 4 into the room or the window shielded by the awning.

From the foregoing description it will be seen that a simple and efficient awning ventilator has been produced which is always in 20 its correct position for use whereby the heated air within the awning will easily pass and be expelled from the interior of the awning while the guiding flap used for directing the heated air to the opening, will 25 also prevent the rays of the sun from passing through the opening into the window shielded by the awning.

What I claim is:—

1. In a device of the class described the 30 combination with an awning having a rectangular transverse extending opening formed adjacent its upper portion, means for reinforcing said opening and a flap carried by said awning, opening upon said awning whereby heated air within said awning may strike upon said flap and then be directed to and expelled through said opening.
2. In a device of the class described the 35 combination with an awning, said awning provided adjacent its upper portion with a transverse extending rectangular opening,

said awning provided with transverse extending integral strips fixedly secured thereto, reinforcing cords passing through one of said strips and having their ends extending transversely across said opening and secured to the remaining strip whereby said opening will be firmly reinforced, and a flap secured to said awning above said opening and depending for a spaced distance below the under surface of the upper portion of said awning whereby the heated air within said awning will pass upwardly and will strike said flap whereby the air 5 will be directed through said opening and expelled from the awning.

3. In a device of the class described the combination with an awning, said awning provided adjacent its upper portion with a 6 transversely extending opening, a flap positioned within said awning, said flap provided with an integral strip fixedly secured to the upper portion of said awning, said flap depending in a vertical position into the 7 body of the awning, said flap being free to move at its ends and lower portion, said flap being adapted to direct the heated air within the awning through said opening.

4. A device of the class described the combination with an awning, said awning provided with a transverse opening formed adjacent its upper portion, means for reinforcing said opening, the upper portion of said awning being bent backwardly upon itself 80 and terminating in an integral depending flap, said flap being formed adjacent said opening whereby said flap will conduct the heated air within said awning through said opening and will constitute a shield for the 85 rays of the sun passing through said opening.

In testimony whereof I hereunto affix my signature in presence of two witnesses.

DAVID R. McGINNIS.
